UNITED STATES PATENT OFFICE.

THOMAS LEGGETT STURTEVANT, OF QUINCY, AND THOMAS JOSEPH STURTEVANT, OF WELLESLEY, MASSACHUSETTS, ASSIGNEES TO STURTEVANT MILL COMPANY, A CORPORATION OF MAINE.

CRUSHING-MILL.

1,083,951.

Specification of Letters Patent.

Patented Jan. 13, 1914.

Application filed November 12, 1910. Serial No. 592,116.

To all whom it may concern:

Be it known that we, THOMAS L. STURTEVANT and THOMAS J. STURTEVANT, citizens of the United States, residing, respectively, 5 at Quincy and Wellesley, in the county of Norfolk and State of Massachusetts, have invented or discovered certain new and useful Improvements in Crushing-Mills, of which the following is a specification, reference being had therein to the accompanying drawings.

This invention relates to that class of crushing mills such as those shown by our Patent No. 906,829, granted December 15, 1908, and 15 our pending application Serial No. 441,857, filed July 3, 1908, and in which the material to be reduced is fed to a rotating anvil ring against the inner face of which it is crushed by coöperating rolls which are forced out- 20 wardly, by spring pressure, toward the interior surface of the said ring. These rings are preferably carried by spoked or open-work heads so that the crushed material is discharged from both sides of the rotating 25 rings, but in this class of mills there is a considerable loss of efficiency by the material tumbling off or escaping from the rings before it passes to the rolls, or before it is properly reduced; and the present invention has for 30 its main object to improve the efficiency of this class of mills by providing means for preventing the too early escape of the material from the rotating anvil rings. This object is effected by a peculiar construction 35 of the anvil ring, or of the feed spout by which the material is fed to the ring, or of the crushing rolls coöperating with the ring, but preferably by all of these means, as will hereinafter more fully appear.

40 In the accompanying drawings Figure 1 illustrates a preferred form of anvil ring with feed spout and coöperating crushing rolls. Fig. 2 is a section of the same, on line 2—2, Fig. 1, and Fig. 3 is a section on line 45 3—3, Fig. 1. Figs. 4 and 5 are detail perspective views of the form of feed spout shown in Figs. 1 and 2, and Figs. 6 and 7 are detail views of another form of feed spout. Fig. 8 is a longitudinal section of a crushing machine in which the present improvements are embodied, and Fig. 9 is a detail view of the feed regulating device of said machine.

50 Referring to the drawings, 12 denotes the anvil ring which will preferably be con-

structed with a transversely concave inner or crushing face, and will also preferably be provided at one edge with an inwardly extending or radial annular lip or flange 13. The material to be crushed is fed to the inner face of the anvil ring through a feed spout 14 which is curved or off-set to one side at its lower end so that it may extend within the anvil ring in such a manner that its discharge portion or mouth is brought 60 into a position at or near the transverse central portion of the ring, so as to deliver the material to the middle of the track of the ring as nearly as possible. This feed spout is preferably provided at one side of its 65 lower end with a curved shield or guard 15 which is on a line with, or in the plane of one side of the ring, or approximately so, and which will prevent the material from escaping at that side of the ring; the inwardly projecting flange 13 preventing the 70 too ready escape of the material from the opposite side of the ring. The outer edge of the shield or guard is curved to conform to the inner face of the anvil ring 12, or 75 approximately so, and is arranged closely adjacent to said face. Said shield or guard 15 may be formed integral with the feed spout, as shown in Figs. 2, 4 and 5, or it may be formed separate from said spout and 80 be detachably secured thereto, as in the construction illustrated in Figs. 6 and 7. To prevent the tendency of the material to escape from the anvil ring, the roll 16, which is next to the feed spout, is preferably con- 85 structed with a grooved or transversely concave face which will act upon the incoming material in such a manner as to squeeze it together and crush it somewhat. The second roll 17, to which the material is next de- 90 livered, is preferably provided with a transversely flat face, which, in coöperation with the transversely concave face of the anvil ring, will still further crush the material, while not unnecessarily crowding the same off 95 the ring. The third roll 18 is preferably provided with a transversely convex face conforming closely in curvature to the concave face of the anvil ring, and if the machine is to include four crushing rolls the 100 fourth roll may also have a convex crushing face. If desired the grooved roll may be omitted and only transversely flat and convex faced rolls be employed, to good effect, in coöperation with the transversely concave 110

anvil ring. By thus providing crushing rolls, having faces of different configuration, the efficiency of the mill is greatly increased in that the different faced rolls acting successively on the material will each cut its own path or roadway so as to act more destructively than is the case with rolls having similar faces, and in that the material will have a greatly lessened tendency to be discharged from the anvil ring before it has been properly reduced. Thus with the use of crushing rolls having faces of different configuration and acting successively on the material to be reduced the tendency to compact the material on the anvil ring is lessened, as each different-faced roll, in cutting a different path, has a tendency to tear up the material rather than to compact it. This efficiency of the mill is also augmented by the shield 15 of the feed spout, or by the inwardly extending flange 13 of the anvil ring, or by both of these features which will preferably be employed in connection with the crushing rolls having differently formed faces, as above described. These crushing rolls having differently formed faces, or faces of different contours, are, in practice, forced outward toward the inner or crushing face of the anvil ring by spring pressure, as fully shown and described in our patent and application above referred to; and as also indicated in Fig. 8 which shows one of the springs 19 which act on the bell-crank roll-carriers 20 to force the rolls outward toward the crushing face of the anvil ring 12 on the rotating anvil ring carrier 11.

The convex faced roll 18 will preferably be arranged at a slight angle to the anvil ring, as shown in Figs. 3 and 8, so as to have a scuffing or rubbing action in addition to its pressing crushing action, thereby still further contributing to the efficiency of the machine in effecting rapid reduction of the material; and if two transversely convex faced rolls be employed they may both be arranged to act as scuffing crushing rolls.

The feed spout 14 conducts the material to be crushed from a hopper 21 to the anvil ring, the feed of the material being regulated by a feed slide 22 which will be so adjusted that the feed spout will not be clogged, thereby permitting the entering material to be discharged tangentially from the feed spout to the anvil ring, in the general direction of rotation of the latter, with a velocity approximating the speed of rotation of the anvil ring, so as to lessen the inertia between the moving ring and the material, and which inertia not only tends to a discharge of the material from the anvil ring but causes wear on the ring by the slip of the hard sharp material thereon. The feed slide is provided with a pin 23 to enter a slot at the elbow of a regulating

lever 24 pivoted at 25 to the hopper. The feed slide may be locked in any position to which it may be adjusted by means of an adjustable block or collar 26 mounted on a hinged bar 27 and provided at its lower side with a notch for engagement with the pin 23 on the feed slide. The adjustable block 26 may be secured in any desired position by means of a set screw 29, thus permitting the feed slide to be locked in any position to which it may be adjusted, the sliding block or collar 26 being of course adjusted on the hinged bar 27 to a position corresponding to the position of adjustment of the feed slide.

It will be understood that the present invention of the differently faced rolls, the flanged anvil ring and the coöperating feed spout, may be applied to an anvil ring and coöperating rolls rotating either in a vertical or horizontal plane; and if the invention be applied to a ring which rotates in a horizontal plane the inwardly extending flange 13 on the anvil ring will preferably be arranged at the lower side thereof; and in such case the feed spout will be correspondingly constructed so that its shield 15 will be arranged at the upper side of the ring.

Having thus described our invention we claim and desire to secure by Letters Patent:

1. In a crushing mill, the combination with an anvil ring, of a feed spout having a discharge opening arranged to deliver material to the central portion of said ring and which feed spout is provided at one side with a curved shield or guard arranged closely adjacent to the edge of the curved inner face of said ring and conforming in shape to the said edge, or substantially so.

2. In a crushing mill, the combination with an anvil ring having an inwardly extending annular lip or flange at one side, of a feed spout to deliver material to the said ring and which feed spout is provided at one side with a curved shield or guard which is arranged at the opposite side of said ring from said lip or flange.

3. In a crushing mill, the combination with a rotating anvil ring having a transversely concave inner or crushing face, and a feed spout for delivering material to said ring, of a series of rolls pressed yieldingly outward toward said ring for the crushing operation, that one of said rolls which is nearest to the delivery end of the said feed spout being constructed with a concave or grooved outer face coöperating directly with said ring.

4. In a crushing mill, the combination with an anvil ring having a transversely concave inner or crushing face, and a feed spout for delivering material to said ring, of a series of rolls coöperating with said ring for the crushing operation, that one of said

rolls which is nearest to the delivery end of the said feed spout being constructed with a concave or grooved outer face and that one of said rolls to which the material will next 5 pass in the crushing operation being provided with a transversely flat crushing face.

5. In a crushing mill, the combination with an anvil ring having a transversely concave inner or crushing face, and a feed 10 spout for delivering material to said ring, of a series of rolls coöperating with said ring for the crushing operation, that one of said rolls which is nearest to the delivery end of the said feed spout being constructed 15 with a concave or grooved outer face, that one of said rolls to which the material will next pass in the crushing operation being provided with a transversely flat crushing face, and that one of said rolls to which the 20 material next passes being provided with a transversely convex outer face.

6. In a crushing mill, the combination with an anvil ring having a transversely curved concave inner face, of a crushing roll 25 having a transversely flat outer face coöperating with the said transversely curved concave face of said anvil ring.

7. In a crushing mill, the combination with an anvil ring having a transversely 30 concave inner face, of a coöperating crushing roll having a transversely flat outer face coöperating with the concave face of said anvil ring, and one or more crushing rolls having a transversely convex outer face 35 or faces.

8. In a crushing mill, the combination with an anvil ring having a transversely concave inner face, of a coöperating crush-

ing roll having a transversely flat face, and 40 a following coöperating roll having a transversely convex face, said last-named roll being inclined relative to said ring so as to act as a scuffing crushing roll.

9. In a crushing mill, the combination 45 with an anvil ring having a transversely concave inner face, of a coöperating crushing roll having a transversely concave face, a second coöperating crushing roll having a transversely flat face, and a following co- 50 operating roll having a transversely convex face, said last-named roll being inclined relative to said ring so as to act as a scuffing crushing roll.

10. In a crushing mill, the combination 55 with a rotating anvil ring, of a series of crushing rolls all coöperating directly with said ring and having faces of different contours and to which rolls the material to be crushed will be successively presented be- 60 tween said rolls and ring.

11. In a crushing mill, the combination with a rotating anvil ring having a trans- 65 versely concave inner or crushing face, of a series of crushing rolls all coöperating di- rectly with said ring and having faces of different contours, and to which rolls the material to be crushed will be successively presented between said rolls and ring.

In testimony whereof we affix our signatures, in presence of two witnesses.
